UNITED STATES PATENT OFFICE.

MAX EISIG, OF NUEREMBERG, GERMANY.

RAIL-FASTENING.

934,054.

Specification of Letters Patent. Patented Sept. 14, 1909.

Application filed April 14, 1908. Serial No. 427,018.

To all whom it may concern:

Be it known that I, MAX EISIG, a subject of the Emperor of Germany, and a resident of Nuremberg, Bavaria, Germany, have invented certain new and useful Improvements in Rail-Fastenings, of which the following is a specification.

My invention relates to the construction of tracks, particularly for street railways, and has for its object to provide an improved means for efficiently fastening and supporting rails in such a manner as to preserve the gage of the track and a good condition of the paving adjacent to the rails.

The invention has particular reference to that class of track construction in which the rails are embedded in concrete, and I have devised novel means for securing a much better connection than hitherto, between the rails and the surrounding concrete.

Various forms of my invention are illustrated in the accompanying drawings, in which Figures 1, 3, 5, 7, 9, 11, 13 and 15 are cross sections, each showing a different form of my invention; Figs. 2, 4, 6, 8, 10, 12, 14 and 16 respectively are corresponding side elevations with the rail support in longitudinal section; and Fig. 17 is a perspective view illustrating the rail of Fig. 9 with the anchoring rods but without the concrete in which it is embedded.

To first give a brief description of the general principle of my invention, I may say that rods extend at short intervals from the rail into the adjacent portion of the concrete paving and form therewith a body of reinforced concrete. The rods are rigidly connected with the rail, as at the web thereof, or at the base, or at both, so that any force tending to displace the rail is transferred to said rods, and as these are firmly united with the concrete by allowing the concrete to set around them, it follows that the concrete holds the rods in place with great tenacity and thus prevents any shifting or bending of the rails.

In all the forms of my invention illustrated by the drawings, A indicates the upper layer of the paving, which may be asphalt, wood, concrete, etc., B the concrete beam or body in which the rails are embedded together with their anchoring rods, and C the supporting mass of broken stone or other suitable material. Only the heads of the rails project from the concrete body B.

Figs. 1 and 2 show a compound rail com-

posed of a main rail D and a guard rail d connected in any suitable manner as by nuts and bolts E. At suitable distances apart (say from four to eight inches), the webs of both rails are perforated in transverse alignment, two superposed sets of perforations being shown. Through these perforations extend the anchoring rods F, f, horizontal at their central portions, inclined toward their ends, and sharply bent at said ends. These rods are embedded entirely in the concrete body B, and during the setting of the concrete they become firmly connected therewith. The inclined portions and bent ends of the rods, while not essential, assist in giving said rods a better hold in the concrete body. Longitudinal rods G, g may be employed in connection with the transverse rods F, f and at the crossing points they may be provided with wire wrappings to connect them temporarily. Wedges such as described below in connection with Figs. 15 and 16 may be employed to firmly secure the transverse rods in the webs of the rails, or other suitable clamping devices may be used. This track construction is very strong inasmuch as the rails are securely anchored, the rods embedded in the concrete and adhering thereto firmly, and connected with the rails, resisting efficiently any strain that may come on the rails, whether vertical, longitudinal, or transverse. In the particular construction illustrated by Figs. 1 and 2, the formation of the transverse anchoring rods with inclined portions and sharply-bent ends or hooks, gives the structure particular strength to resist strains acting on the rails vertically and laterally.

In Figs. 3 and 4, the concrete contained between the main rail D' and the guard rail d' is not exposed, the heads of the two rails being in contact with each other. The nuts and bolts E', and the upper sets of transverse anchoring rods F', are practically of the same construction and arrangement as the corresponding parts E, F of Figs. 1 and 2. The base of the main rail D' has vertical perforations through which pass upright rods H likewise embedded in the concrete body B and preferably with their lower ends bent outward to form hooks as shown. The longitudinal rods G' would in this case be connected not only with the transverse approximately horizontal rods F', but with the vertical rods H as well.

In Figs. 5 and 6 the grooved rail D² has

horizontal perforations in its web for the passage of the transverse anchoring rods F^2 , and vertical perforations in its base for the passage of the upright rods H' having hooks 5 at their lower ends and converging at their upper ends toward the web of the rail and the longitudinal rods G^2 .

Figs. 7 and 8 show a grooved rail D^3 having two sets of horizontal perforations in its web at different levels, to receive two sets of transverse rods F^3, f' , of substantially the same character as the upper set of rods F in Fig. 1. Rods of the two sets are however staggered, that is, not directly superposed 10 as in Figs. 1 and 2, and the rods f' of the lower set are shown out of contact with the rail base, whereas in Figs. 1 and 2 the lower rods f engage the rail bases. There are also 15 two sets of longitudinal rods G^3, g' .

In Figs. 9 and 10 the rail D^4 is perforated in substantially the same manner as in Figs. 5 and 6. The transverse anchoring rods F^4 are horizontal, except for the hooks at their ends. The upright rods H^2 are practically 25 the same as in Figs. 3 and 4, and both sets of rods are connected by longitudinal rods G^4 . Fig. 17 shows the rail and rods as they appear before they are embedded in the concrete body.

In Figs. 11 and 12 the arrangement of the perforations in the web of the rail D^5 is substantially the same as in Figs. 7 and 8. The upper anchoring rods F^5 are similar to the rods F^4 of Figs. 9 and 10 and are connected 35 by longitudinal rods G^5 . The lower transverse rods f^2 are similar to the rods f of Figs. 1 and 2, being bent into engagement with the edges of the rail base and formed with hooks at their ends.

Figs. 13 and 14 illustrate a construction in which the anchoring rods terminate at the rail D^6 , that is, one end of each rod (and not its central portion) is secured to the rail, as for instance by riveting. There are 45 transverse rods F^6 disposed in staggering fashion at different heights and some projected to the left of the rail while others extend toward the right. The vertical rods H^3 project partly upward and partly downward from the rail base. In this specific instance, I have shown the rail as resting upon a concrete beam or longitudinal tie J , in which the downward rods H^3 are embedded. The same kind of rail support or 55 tie is shown in Figs. 15 and 16, in which however each vertical rod H^4 extends both above and below the base of the rail D^7 , and each of the transverse rods F^7, f^3 both to the left and to the right of the rail web. All 60 rods are perfectly straight in Figs. 13 to 16. Longitudinal rods G^6, g^2 are provided in the construction illustrated by Figs. 15 and 16, in two sets to connect the upper and lower sets of transverse rods F^7 and f^3 respectively. The rods of these two sets are stag- 65

gered and not superposed. Crescent-shaped wedges K are shown in Figs. 15 and 16 as means for firmly securing the rods F^7, f^3, H^4 to the rail, this expedient being similar to that employed in electric rail bonds.

The improved track construction herein described may be employed for railways of all kinds, but especially street railways, and also for tracks on which ordinary trucks or carriages are intended to travel.

It will be understood that in each of the constructions shown, anchoring members project from the web of the rail at each side thereof, the ends of such members being preferably at approximately equal distances from said web, so that the web is strengthened equally against lateral strains in either direction. The ends of such anchoring members are free, that is to say, they are not connected with the other rail and thus 30 differ essentially from tie rods such as have been used in some prior constructions. The anchoring members employed by me not only strengthen the resisting power of the web against lateral strains, but further assist in taking up vertical strains and also longitudinal strains tending to cause a creeping of the rail.

I claim as my invention;

1. In track construction, a rail, a body of 95 concrete in which said rail is embedded, and anchoring members connected rigidly with the web of the rail and extending therefrom at each side to approximately the same distance, said anchoring members being embedded in said body of concrete.

2. In track construction, a rail, a body of concrete adjacent thereto, and anchoring members connected rigidly with the web of the rail and extending at each side of the 105 web to about the same distance therefrom into said concrete body.

3. In track construction, a rail, a body of concrete adjacent thereto, and anchoring members secured to the web of the rail rigidly and projecting at each side thereof into 110 said body of concrete.

4. In track construction, a rail, a body of concrete adjacent thereto, and anchoring members projecting into the concrete body, 115 some of said members being connected rigidly with the base of the rail and extending upward and downward therefrom, while other members are connected rigidly with the web of the rail and extend at each side 120 thereof.

5. In track construction, a rail, a body of concrete in which said rail is embedded, and anchoring members projecting into said concrete body, some of said members being rigidly secured to the base of the rail and extending upward and downward therefrom, while other members are connected rigidly with the web of the rail and extend at both 125 sides thereof.

6. In track construction, a rail, a body of
concrete in which said rail is embedded, and
anchoring members projecting into the con-
crete body, some of said members extending
5 through the base of the rail, and others
through its web.

In testimony whereof I have hereunto set

my name in the presence of two subscribing
witnesses this 25th day of March 1908.

MAX EISIG.
